HOLDER FOR TOILET ARTICLES

Robert H. Cornett, Culver City, Calif.

Application October 28, 1955, Serial No. 38,609

Term of patent 14 years

(Cl. D86—10)

Fig. 1 is a front perspective view of a holder for toilet articles showing my new design.

Fig. 2 is a left end elevational view of Fig. 1; and

Fig. 3 is a top plan view of Fig. 1.

The articles shown in broken lines are for the purpose of illustration only.

I claim:

The ornamental design for a holder for toilet articles, substantially as shown and described.
